(57) CLAIM

The ornamental design for a pallet for holding materials such as seed bins and the like, as shown and described.

DESCRIPTION

FIG. 1 is a perspective view of a pallet for holding materials such as seed bins and the like showing my new design;

FIG. 2 is a top plan view of the pallet of FIG. 1.

FIG. 3 is a side view of the pallet of FIG. 1;

FIG. 4 is another side view of the pallet of FIG. 1;

FIG. 5 is a bottom plan view of the pallet of FIG. 1; and,

FIG. 6 is a perspective view of the bottom of the pallet of FIG. 1.
